UNITED STATES PATENT OFFICE

MARSHALL R. KENNEDY, OF SAN FRANCISCO, CALIFORNIA

GAME

Application filed February 4, 1928. Serial No. 251,905.

This invention relates to improvements in games and has particular reference to a football game.

The principal object of this invention is to produce a game board wherein all the movements of a football game may be followed.

A further object is to produce a game board which may be economically manufactured.

A still further object is to produce a game board which will be instructive in the game thereby teaching the rudiments of the game.

Other objects and advantages will be apparent during the course of the following description.

15 In the accompanying drawings forming a part of this specifications and in which like numerals are employed to designate like parts throughout the same,

Figure 1 is a top plan view of a game board constructed in accordance with my invention.

Figure 2 is a side elevation of Figure 1, and Figure 3 is an end elevation of Figure 1.

Applicant is aware of the fact that various 25 game boards have been created for the purpose of simulating the football game. These boards in most instances merely represented a football grid over which playing pieces were moved to indicate various plays. It has 30 also been common to employ charts which represent a football grid and to mark upon the chart the various plays as the same were performed by given teams. Of late it is quite common to radio broadcast important 35 football games and in order to keep accurate tract of the play, the listener often employs a chart with the result that when the announcer states that a thirty-seven yard run has been made, the listener must figure up 40 on his chart where thirty-seven yards would be from the point upon where the ball last rested. This often takes a great length of time so that the following play being made by the team and being announced by the broad- 45 caster is lost to the listener.

Applicant has therefore devised a board 50 wherein the listener at a glance can tell exactly where the ball should be moved to and then move the ball to the designated spot without stopping to figure by either adding

or subtracting the number of yards the ball is to be moved.

In the accompanying drawings wherein for the purpose of illustration is shown a preferred embodiment of my invention, the 55 numeral 5 designates a base board upon which is secured a chart comprising sections 6, 7, 8 and 9. This chart is preferably cemented or otherwise secured to the base board 5 and carries the necessary indicia for the 60 playing of the game.

It will be noted that the sections 6 and 7 and the sections 8 and 9 are separated from each other so as to provide runways 11 and 12 respectively. These runways serve to accommodate a slider 13 which slider designates the yard marker. It will also be noted that the sections 7 and 8 are spaced apart and at the same time they overlie a recess 14 formed in the board 5. This results in a T- 70 shaped slot in which a slide rule 16 is positioned. This slide rule carries a field piece 17 upon which a miniature ball 18 is secured.

Marked upon the surface of the slide rule 16 is indicia reading from the field piece 75 toward each end of the slide rule. The indicia carried on the sections 6 and 9 are so arranged that they read from the goal lines toward the center of the field. This results in the readings at the sides of the field being 80 opposite to the readings upon the slide rule.

In order to follow a play upon the board we will assume that the ball is at the forty yard line on the A portion of the field and that a run of twenty-five yards is made to- 85 ward the B side of the field. By looking upon the slide rule to the B side of the field it will immediately be seen that a twenty-five yard run would place the ball upon the thirty-five yard line of B side, or if the run had 90 been forty yards, the ball would be upon the twenty yard line of the B side. By now moving the slide rule so that the ball is moved twenty-five yards or forty yards as the case may be, the next successive movement of the 95 ball can be easily made by again observing on the slide rule the number of yards the ball is to be moved either to one side of the field or the other.

It will thus be seen that I have produced 100

a game board which will accomplish all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the 10 subjoined claims.

Having thus described my invention, I claim:—

1. In a game board, a base having numerical indicia position thereon, a slide rule positioned on said board, numerical indicia carried by said slide rule, the indicia on said slide rule being oppositely disposed from that on said game board.
2. In a game board of the character described, a base, an indicia bearing element positioned on said base, said indicia element being divided, a slide rule positioned between two of the sections of said indicia bearing element, the indicia on said slide rule being oppositely disposed from the indicia bearing element for the purpose specified.
3. In a game board, a base, indicia bearing element positioned on said base and spaced one from the other, a slide rule adapted to be positioned between two of said indicia bearing elements, a field piece secured to said slide rule, a marker adapted to be slidably positioned between said indicia bearing members at a point remote from said slide rule.
4. In a game board, a base, indicia bearing elements positioned on said base and spaced one from the other, a slide rule adapted to be positioned between two of said indicia bearing elements, a field piece secured to said slide rule, indicia formed on said slide rule, indicia on said slide rule reading in opposite directions from said field piece, markers adapted to be slidably positioned between certain of said indicia bearing members and at a point remote from said slide rule.

In testimony whereof I affix my signature.
MARSHALL R. KENNEDY.
